TESTING OR INSPECTING MACHINE

Harry D. Stephens, Bristol, Conn., assignor, by
mesne assignments, to General Motors Corpora-
tion, Detroit, Mich., a corporation of Dela-
ware

Application January 24, 1933, Serial No. 653,281

7 Claims. (Cl. 175—183)

This invention relates to testing or inspecting machines and comprises all of the features of novelty herein disclosed. An object of the invention is to provide an improved machine and 5 method for testing articles, especially steel articles, to detect soft spots or the lack of uniformity in hardness. Another object is to provide a machine utilizing the magnetic properties or permeability of the metal to indicate its uniformity 10 or lack of uniformity in structure. Another object is to provide improved apparatus for supporting and rotating round articles to subject them to a test.

To these ends and also to improve generally 15 upon machines of this character, the invention consists in the various matters hereinafter described and claimed. In its broader aspects, the invention is not necessarily limited to the specific construction selected for illustrative purposes in 20 the accompanying drawings in which

Fig. 1 is a sectional view on the line 1—1 of Fig. 6 with some parts in side elevation.

Fig. 2 is an enlarged view of certain levers with a portion of their supporting bracket in section.

Fig. 3 is an enlarged side view of a plunger and associated parts.

Fig. 4 is a front view of the plunger and its operating cam.

Fig. 5 is an enlarged front view of a roller carrier.

Fig. 6 is a front elevation of the machine with parts in section on the line 6—6 of Fig. 1.

Fig. 7 is a diagram.

The work-piece W, herein shown as a steel roller 35 for friction clutches or the like, is supported by a pair of idler rollers 10 and a driving roller 12 all of which are preferably non-magnetic and grooved to reliably support the work-piece for rotation, as in a vertical plane. The driving roller 40 12 is preferably composed of felt compressed and bolted between metal side discs 14, and the idler rollers 10 are preferably of brass. The driving roller 12 is fixed to the front end of a drive shaft 16 which is journalled in bearing blocks 18 on 45 the top of a bracket 20. The bracket has a vertical web 21 joined to vertical bosses or sleeves 22 (Fig. 6) which are adjustably secured by set-screws 24 to upright posts 26 on a frame 28 having supporting legs 30. As will appear, the shaft can 50 be clutched to a cam which operates a series of control switches.

The idler rollers 10 are journalled between side rails 32 of a yieldable carrier (Figs. 5 and 6) which can be raised and lowered to provide 55 for inserting or removing the work. The ends of

the rails 32 are connected by blocks 34 supported on plungers 36 which are guided vertically by openings in lugs 38 and 40 on the frame. Coil springs 42 are interposed between the lugs 40 and abutment washers 44 on the plungers whereby the idler rollers are urged yieldingly upwards against the work and so hold the work against the friction driving roller 12. The lower ends of the plungers are shouldered and secured by nuts 45 to a cross bar 46 having connection with 10 a treadle. Depending lugs 48 on the cross bar are pivoted by a pin 50 to an arm 52 (Fig. 1) on a treadle lever 54, the lever being pivoted on a shaft 56 secured in depending lugs 58 on the frame. Sleeves 60 surround the shaft and serve 15 to space the lever from the lugs. An upright arm 62 on the lever is connected by a coil spring 64 to a screw 66 adjustably anchored on a frame part 68. The coil spring 64 urges the treadle lever counterclockwise in Fig. 1 and resulting upward 20 movement of the idler rollers, when there is no work in the machine, is limited by the engagement of the cross bar 46 with the frame lugs 40.

A transformer, having a primary coil 70 and two pairs of secondary coils 72 and 74, is yieldably supported from the cross bar 46, and the core laminations 76 pertaining to the upper pair of secondary coils 72 are urged against the rotating work-piece which thereby completes a path for the magnetic flux. The laminations 76 have their upper ends unconnected and free to project between the side rails 32 and are desirably shaped to conform to the periphery of the work-piece. The laminations are united or continuous at their lower ends so that the magnetic field pertaining 35 to the lower pair of secondary coils 74 is a constant. The transformer parts are held in a yoke 80 by clamping plates 82. The yoke has vertical openings at its ends to slide on plungers 84 whose lower ends are shouldered and clamped by nuts 40 86 to the cross bar 46. Coil springs 88, interposed between the yoke ends and collars 90 on the plungers, urge the transformer parts upwardly until the laminations 76 engage the work-piece.

Power for driving the roller 12 is supplied from 45 a motor 100 to speed reducing gearing in a casing 102 from which projects a countershaft 104 having a sprocket wheel 106 engaging a sprocket chain 108 which drives a sprocket wheel 110 on the shaft 16. Splined on the shaft 16 is a grooved 50 clutch collar 112 having clutch teeth arranged to engage co-operating teeth on a cam 114 whose hub is loosely journalled on the shaft 16. When the clutch is thrown in by mechanism herein-after described, the cam makes one revolution 55

and actuates a series of controlling switches. The cam projects downwardly through a slot in the bracket 20 and engages a roller 116 journalled in a fork 118 at the upper end of a sliding plunger 120 which is guided vertically by guide brackets 122 fastened on the vertical web 21 of the bracket 20. The plunger is urged upwardly by a coil spring 124 interposed between one of the brackets 122 and an abutment 126 on the plunger. 5 Projecting laterally from the fork 118 (see Fig. 3), through a slot 128 in the web 21, is a bar 130 which is tapped to receive an adjustable screw 132 having a lock nut 134. The lower end of the screw abuts against a plate 136 fastened to a block 138 which is pivoted on a shaft 140 mounted in lugs 142 on the web 21 of the bracket 20. A coil spring 144 holds the plate 136 against the screw 132 so that the block 138 will rock or tilt with a vertical movement of the plunger 120. Held by 10 spring clips 146 on the tiltable block 138 is a series of mercury switches indicated on the diagram by numerals 150, 152 and 154. Thus it will be seen that one revolution of the cam 114 will tilt the mercury switches, first from a normal position 15 and then back again.

In order to throw the clutch to start the rotation of the cam, the following mechanism is provided. (See Figs. 1, 2 and 6.) Rollers 150 project into a groove of the clutch collar 112 from 20 arms 158 which are pinned to rock shafts 160 journalled in lugs on the top of the bracket 20. Arms 162 are also pinned to the rock shafts and project downwardly through holes in the bracket 20. The lower ends of the arms 162 are slotted 25 to provide lost-motion pivot connections with pivot pins 164 carried by levers 166 which are pivoted at 167 to lugs 168 depending from the bracket 20. Each lever 166 is pivoted to one of the arms of a yoke 170 which straddles the 30 lower portion of a solenoid 172 hung on the bracket 20. The middle of the yoke has an aperture for a stud 174 whose upper end is pinned loosely to the lower end of the core or plunger 176 of the solenoid. A coil spring 178 is interposed between the yoke and an adjusting nut 180 on a threaded portion of the stud 174 whereby a yielding connection is provided to compensate for a possible overrun of the solenoid plunger. From the foregoing, it is apparent that an 35 energizing of the solenoid will act through the yoke and lever system to throw in the clutch and start rotation of the cam 114. The switches will thus be tilted, under control of the cam, first in one direction and then in the other. The 40 switches control a cycle of the machine.

Referring to the diagram, the driving motor 100 is started by closing a switch 181 to complete a circuit in line wires 182 and 184. A pilot light or signal lamp 186 is lit by closing a switch 188 45 and this light indicates that current is being supplied to the testing instruments. One of the instruments made ready for action is a transformer 190 controlling a lamp 192 in a circular casing 194 and another is the field winding 196 of an 50 alternating current reflecting galvanometer 198 having a mirror 200 and an armature winding 202. The lamp casing 194 has a small hole 204 bisected by a wire 206 on an apertured plate 208. A circular ray of light with a bisecting shadow 55 is thus directed through a lens 210 to the mirror 200 and is reflected to a frosted glass 212 having a marker 214 to indicate a neutral position. The lens 210 is suitably held in a vertically adjusted position by a screw 218 on the vertical leg of an 60 angle bracket 220 which is slotted and held in 65

horizontally adjusted position on a plate 222 by a clamping screw 224. These instruments are contained in a box 226 (Fig. 6) supported by posts 228 from the bracket 20.

Upon actuating the treadle lever 54, a work-piece W can be placed between the rollers for rotation. To start a cycle for testing the piece, a push button switch 230 is actuated momentarily and this energizes the solenoid 172 and throws in the clutch 112 for rotating the cam 114. The 10 cam quickly depresses the plunger 120, and the switches 150 and 154 are closed, and switch 152 (which is normally closed) is opened. The switch 152 is normally closed for the purpose of short-circuiting the armature windings 202 and is set 15 to open just after the switch 154 is closed in order to prevent abnormal needle deflection during the instant of building up magnetizing current. When the switch 152 is opened, the position of the mirror is controlled by the condition of the 20 work-piece as will appear. The closing of the switch 150 by the cam holds the solenoid active after the push button switch 230 is released and this condition is maintained until the completion of one revolution of the cam opens the 25 switch and de-energizes the solenoid. The roller 14 makes one revolution and is of a selected diameter larger than the work-piece so as to insure at least a full revolution of the work-piece during the testing cycle.

When the remaining switch 154 is closed by the cam, a circuit is completed through the primary winding 70 and through a condenser 232 which governs the amount of current in the primary and the phase relationship of that current to the 30 current in the galvanometer field. An ammeter 234 is also in this circuit. The secondary windings 72 have an induced current which is influenced by the lack of uniformity in hardness of the work-piece W engaging their laminations 78. 40 In the preliminary set up, a master work-piece of acceptable hardness and uniformity is placed in the flux field of the secondary windings 72 and potentiometers 236 and 238 are adjusted until the flow of currents in both secondary windings 72 45 and 74 balance one another with the mirror in a neutral position with the reflected shadow at the marker 214. A resistance 240 is placed in the circuit of the secondary windings 72 to prevent burning out the armature windings 202 and a 50 similar resistance 242 is placed in the circuit of the secondary windings 74. A variable shunt 244 is placed across the terminals of the armature windings 202 to shunt excessive current from the armature. If the piece being tested 55 lacks the uniformity in hardness required for an acceptable article, its permeability or some other physical property will vary from the standard and the lack of balance in the currents of the secondary windings 72 and 74 will cause the 60 mirror 202 to swing. The reflected image will swing to one side or the other of the marker 214 and furnish a visual indication of the amount of variation in hardness so that the operator can determine whether to reject the piece. Not only 65 is variation in hardness at different portions of the piece indicated but if the piece as a whole varies from the master piece, that fact is also indicated.

I claim:

1. In apparatus for testing a round work-piece, a core structure comprising a complete magnetic loop and an interrupted loop, the latter having legs spaced apart and curved at their ends to conform to the periphery of the work-piece,

means for supporting and rotating the work-piece with spaced portions of its periphery in contact with the ends of said legs whereby a sector of the rotating work-piece completes the interrupted loop, means for yieldingly urging the legs of the core and the periphery of the work-piece into contact, means for producing a flow of magnetic energy in each loop, and means for comparing said flows to determine the physical characteristics of the work sectors rubbing across the ends of said legs; substantially as described.

5. In apparatus for testing a round work-piece, a plurality of rollers angularly spaced about the periphery of the work-piece to engage said periphery, and support the work-piece for rotation, a core structure having a pair of spaced legs engaging the periphery of the work-piece whereby a sector of the rotating work-piece magnetically connects said legs to complete a magnetic circuit, the said core also having another pair of permanently connected legs forming a constantly closed magnetic circuit independent of the work, means for producing a flow of magnetic energy in each circuit, and means for comparing said flows to determine the physical characteristics of the work sectors rotating across the first mentioned pair of legs; substantially as described.

10. In apparatus for testing a round work-piece, a driving roller and a pair of supporting rollers angularly spaced about the periphery of the work-piece, means for urging the supporting rollers towards the driving roller to hold the work-piece for rotation by engagement with the periphery thereof, a testing device, means for urging the testing device into contact with the work-piece, and actuating means for simultaneously moving the testing device and the supporting rollers away from the driving roller; substantially as described.

15. In apparatus for testing a round work-piece, a plurality of rollers angularly spaced about the periphery of the work-piece to engage said periphery, and support the work-piece for rotation, a core structure having a pair of spaced legs engaging the periphery of the work-piece whereby a sector of the rotating work-piece magnetically connects said legs to complete a magnetic circuit, the said core also having another pair of permanently connected legs forming a constantly closed magnetic circuit independent of the work, means for producing a flow of magnetic energy in each circuit, and means for comparing said flows to determine the physical characteristics of the work sectors rotating across the first mentioned pair of legs; substantially as described.

20. In apparatus for testing a round work-piece, a driving roller and a pair of supporting rollers angularly spaced about the periphery of the work-piece, means for urging the supporting rollers towards the driving roller to hold the work-piece for rotation by engagement with the periphery thereof, a testing device, means for urging the testing device into contact with the work-piece, and actuating means for simultaneously moving the testing device and the supporting rollers away from the driving roller; substantially as described.

25. In apparatus for testing a round work-piece, a plurality of rollers angularly spaced about the periphery of the work-piece to engage said periphery, and support the work-piece for rotation, a core structure having a pair of spaced legs engaging the periphery of the work-piece whereby a sector of the rotating work-piece magnetically connects said legs to complete a magnetic circuit, the said core also having another pair of permanently connected legs forming a constantly closed magnetic circuit independent of the work, means for producing a flow of magnetic energy in each circuit, and means for comparing said flows to determine the physical characteristics of the work sectors rotating across the first mentioned pair of legs; substantially as described.

30. In apparatus for testing a round work-piece, a driving roller and a pair of supporting rollers angularly spaced about the periphery of the work-piece, means for urging the supporting rollers towards the driving roller to hold the work-piece for rotation by engagement with the periphery thereof, a testing device, means for urging the testing device into contact with the work-piece, and actuating means for simultaneously moving the testing device and the supporting rollers away from the driving roller; substantially as described.

35. In apparatus for testing a round work-piece, a driving roller and a pair of supporting rollers angularly spaced about the periphery of the work-piece, means for urging the supporting rollers towards the driving roller to hold the work-piece for rotation by engagement with the periphery thereof, a testing device, means for urging the testing device into contact with the work-piece, and actuating means for simultaneously moving the testing device and the supporting rollers away from the driving roller; substantially as described.

40. 4. In apparatus of the character described, a

driving roller to engage the periphery of a round work-piece, a carrier having side rails, work-supporting idler rollers journaled between the side rails, plungers connected to the carrier and guiding it towards and from the driving roller, springs for urging the carrier towards the driving roller, and means for retracting the carrier; substantially as described.

5. In apparatus of the character described, a driving roller to engage the periphery of a round work-piece, a carrier having side rails, work-supporting idler rollers journaled between the side rails, plungers connected to the carrier and guiding it towards and from the driving roller, springs for urging the carrier towards the driving roller, a work testing device yieldably connected to the carrier, and means for moving the carrier and the testing device away from the driving roller; substantially as described.

10. In apparatus of the character described, a driving roller to engage the periphery of a round work-piece, a carrier having side rails, work-supporting idler rollers journaled between the side rails, plungers connected to the carrier and guiding it towards and from the driving roller, springs for urging the carrier towards the driving roller, a work testing device yieldably connected to the carrier, and means for moving the carrier and the testing device away from the driving roller; substantially as described.

15. In apparatus of the character described, a driving roller to engage the periphery of a round work-piece, a carrier having side rails, work-supporting idler rollers journaled between the side rails, plungers connected to the carrier and guiding it towards and from the driving roller, springs for urging the carrier towards the driving roller, a work testing device yieldably connected to the carrier, and means for moving the carrier and the testing device away from the driving roller; substantially as described.

20. In apparatus of the character described, a drive shaft having a driving roller to engage the periphery of the work-piece, a testing device having a core to engage the periphery of the rotating work-piece, means for energizing the testing device, a cam supported by the drive shaft, a shiftable clutch for connecting the cam to the drive shaft, and a switch actuated by the cam for controlling the energizing means; substantially as described.

25. In apparatus of the character described, a drive shaft having a driving roller to engage the periphery of the work-piece, a testing device having a core to engage the periphery of the rotating work-piece, means for energizing the testing device, a cam supported by the drive shaft, a shiftable clutch for connecting the cam to the drive shaft, and a switch actuated by the cam for controlling the energizing means; substantially as described.

30. In apparatus of the character described, a drive shaft having a driving roller to engage the periphery of the work-piece, a testing device having a core to engage the periphery of the rotating work-piece, means for energizing the testing device, a cam supported by the drive shaft, a shiftable clutch for connecting the cam to the drive shaft, and a switch actuated by the cam for controlling the energizing means; substantially as described.

35. In apparatus of the character described, a drive shaft having a driving roller to engage the periphery of the work-piece, a testing device having a core to engage the periphery of the rotating work-piece, means for energizing the testing device, a cam supported by the drive shaft, a shiftable clutch for connecting the cam to the drive shaft, and a switch actuated by the cam for controlling the energizing means; substantially as described.

HARRY D. STEPHENS. 40
